M. MENKIN.
BUTTON AND METHOD OF MAKING THE SAME.
APPLICATION FILED FEB. 24, 1919.

Patented Feb. 3, 1920.

UNITED STATES PATENT OFFICE.

MAX MENKIN, OF NEW YORK, N. Y.

BUTTON AND METHOD OF MAKING THE SAME.

1,329,791.

Specification of Letters Patent.

Patented Feb. 3, 1920.

Application filed February 24, 1919. Serial No. 278,782.

To all whom it may concern:

Be it known that I, MAX MENKIN, a citizen of Russia, and resident of the borough of the Bronx, county of the Bronx, city and 5 State of New York, have invented certain new and useful Improvements in Buttons and Methods of Making the Same, of which the following is a specification.

The present invention relates to improvements in buttons and methods of making the same and more particularly the invention contemplates buttons of the type known as rimmed buttons presenting in appearance a button having a central portion and a rim 15 portion surrounding the same.

According to my improvements, I propose to provide a button of this character having a central button portion covered with cloth and a rim portion surrounding 20 the same, and if desired also covered with cloth preferably of a different kind, the button lending itself in this respect particularly well to garments which are made from two different materials, the button being covered 25 with the same materials. It is an object of the invention to enable the manufacture of such buttons in a simple and economical manner and to provide a substantially neater button than has heretofore been produced and a structurally improved button.

With these and other objects in view, an embodiment of my invention is shown in the accompanying drawings and this embodiment will be hereinafter more fully described with reference thereto and the invention will be finally pointed out in the claims.

In the accompanying drawings:

Figure 1 is a plan view of a circular piece 40 of material for covering the rim portion of the button;

Fig. 2 is a plan view of the rim frame;

Fig. 3 is a sectional view thereof taken along the line 3—3 of Fig. 2;

Fig. 4 is an inside plan view of the rim-back;

Fig. 5 is a sectional view thereof taken along the line 5—5 of Fig. 4;

Fig. 6 is a sectional view showing the 50 covering material, the rim-frame and the rim-back in their relation before assembling;

Fig. 7 is a similar view showing these parts assembled;

Fig. 8 is a similar view showing the parts

assembled and the rim-frame clenched over the rim-back;

Fig. 9 is a similar view showing the covering material perforated centrally;

Fig. 10 is a top plan view of the covered 60 rim and back;

Fig. 11 is a bottom plan view thereof;

Fig. 12 is a side elevation of the button portion to be attached to the covered rim and back;

Fig. 13 is a vertical sectional view 65 thereof;

Fig. 14 is a view partly in elevation and partly in section showing the button portion and the covered rim and back portion as- 70sembled;

Fig. 15 is a similar view showing the button portion secured to the rim and back portion;

Fig. 16 is a top plan view of the finished 75 button; and

Fig. 17 is a bottom plan view thereof.

Similar reference characters indicate corresponding parts throughout the several figures of the drawings.

According to the drawings the rim-frame 20 shown in Figs. 2 and 3 is in the form of a circular ring, the peripheral portion 21 of which is cylindrical while the inner portion 22 is inclined downwardly but is of substantially less depth than the portion 21, the upper surface of the frame being rounded to produce, as will hereinafter appear, the contour of the covered rim when completed. It will therefore be understood that this shape 90 may be varied as desired, that is, it may be flat and provided with sharp corners in which case the rim portion of the button will have this shape.

The rim-back portion 23 is of smaller 95 diameter than the rim portion 20, the upstanding peripheral portion 24 being such that it will fit into the recess formed by the under side of the rim 20. The central portion of the rim-back is raised as at 25, providing at the under side of the same a dished portion or recess which is provided centrally with an aperture or perforation 26, said recessed portion annularly surrounding the said aperture.

The piece of material 27 to cover the rim, which is shown in Fig. 1, is unperforated and is of such greater diameter than the rim that it may be placed over the same and have its edges brought down along the periph- 110

2

eral portion 21 and beneath the rim. The rim-back is thereupon pressed into place at the under side of the rim frame forcing the marginal portion of the material into the recess at the under side of the frame as clearly shown in Fig. 7 and stretching the material across the rim frame substantially tight. The peripheral portion 21 is thereupon clenched in the usual manner by button 10 ton making dies or other suitable machine means over the rim-back as shown at 21^a, Fig. 8, thereby securing the parts together and securing the cloth so that it covers the rim. The cloth is then perforated centrally 15 as at 28, the perforation being in register with the perforation 26 of the rim-back. It is important that the cloth be perforated at this time, rather than before assembling of the parts as the same may thereby be accurately positioned and will not be stretched 20 out of shape as would be the case if the perforation were made previous to the assembling of the parts. I may also if desired however, cut the perforation 28 at the same time as cutting the cloth, this being 25 preferably done by means of single cutting die. The covered rims and backs may furthermore be furnished in their covered state before securing the button portion thereto and kept in stock in this manner 30 unperforated so that there is no danger of the perforation becoming stretched and the material raveling. When the covered rim is to be used in connection with the button 35 portion, the cloth should be perforated as shown in Fig. 9, whereupon the button portion may be secured thereto as will presently be described.

Referring to Figs. 12 and 13, the button portion comprises a convex shell 30 having a downwardly extending rim portion 31 and over which the cloth covering 32 is placed and held thereon by a back portion 33 inserted into the under side of the shell and secured by clenching the portion 31 of the shell over the sides of the back portion 33 in the usual manner by button making dies or other suitable machine means. The portion 33 is provided with a plurality of downwardly extending prongs 34 struck from the same material from which the back is made, these prongs being preferably four in number and pointed. A tuft 35 is disposed within the button portion and projects 45 through the central opening within the prongs. The prongs as it is clear from Fig. 12, form upon the button a substantially cylindrical shaped shank which is inserted through the perforations 28 and 26 of the cloth covering 27 and the rim-back 26, the button portion being pressed down tightly 50 upon the cloth covering 27 thereby stretching the shape as is shown in Fig. 14 and by spreading out the prongs 34 into the dished 55 portion 25 of the rim-back the button portion 60

is secured in place, the dished portion 25 receiving the prongs in such manner that they are substantially flush with the under side of the rim-back so that the back of the finished button presents a substantially 70 smooth surface free from projections, which might be caught into the material of the garment upon which the button is placed.

While I have shown an improved type of tufted button for use in connection with the 75 covered rim and back it will be understood that an uncovered or other type of button may be used as well, and the same may be of any desired shape. It may, if desired, be provided with pins or staples adapted to 80 be passed through the cloth 27 and aperture 26 through the material to which the button is to be attached, and upset at the under side thereof. It may also have sewing holes in which case the sewing thread will pass 85 through the cloth 27 of the rim-back to the material to which the button is to be attached, and for this purpose the cloth 27 is preferably not provided with the hole 28. The rim-frame and rim-back, as also the 90 shell and back of the tufted button portion, it will be understood, are preferably formed of thin sheet metal stamped into shape and the parts are adapted to be assembled by means of button making machines of the 95 usual type.

I have illustrated and described preferred and satisfactory embodiments of my invention but it is obvious that changes may be made therein within the spirit and scope 100 thereof as defined in the appended claims.

I claim:

1. In a button, a rim portion provided with a covering and perforated centrally, a central button portion disposed at the upper side of said rim portion of smaller diameter than said rim portion, and means on said button portion engaging the perforation of said rim portion adapted to secure said button portion to said rim portion 110 independently of the securing of said covering to said rim portion.

2. In a button, a rim portion provided with a covering and perforated centrally, a central button portion disposed at the 115 upper side of said rim portion of smaller diameter than said rim portion, means on said button portion engaging the perforation of said rim portion adapted to secure said button portion to said rim portion independently of the securing of said covering to said rim portion, and means independent of said securing means for attaching said button to a garment or the like.

3. In a button, a rim-frame, covering for 125 said rim-frame extending over the same and having its edges folded beneath the same, a centrally perforated back portion engaged with said rim-frame and securing said covering in place, said rim-frame being 130

permanently clenched upon said back portion, said covering being stretched tight across the space within said rim-frame extending at its ends between said rim-frame 5 and said back portion, and secured at its ends by clenching of said rim-frame.

4. In a button, a rim-frame, covering for said rim-frame extending over the same and having its edges folded beneath the 10 same, a centrally perforated back portion engaged with said rim-frame and securing said covering in place, said rim-frame being permanently clenched upon said back portion, said covering extending over the space 15 within said rim-frame, a central button portion disposed at the upper side of said rim-frame and back portion of smaller diameter than said rim-frame and back portion, and means on said button portion extending 20 through said covering and through said perforation of said back portion, and adapted 25 to secure said button portion to said rim-frame and back portion independently of the securing of said rim-frame to said back portion.

5. In a button, a rim-frame, covering for said rim-frame extending over the same and having its edges folded beneath the same, a centrally perforated back portion 30 engaged with said rim-frame and having an annular recess surrounding the said perforation at its under side, said rim-frame being permanently clenched upon said back portion and securing said covering in place, 35 a central button portion disposed at the upper side of said rim-frame and back portion of smaller diameter than said rim-frame and back portion, and a shank on said central button portion extending 40 through said cover and through said perforation of said back portion and provided with prongs upset upon said back portion and disposed within said annular recess of said back portion and adapted to secure 45 said button portion to said rim-frame and back portion independently of the securing of said back portion to said rim-frame.

6. In a button, a rim-frame, covering for said rim-frame extending over the same and 50 having its edges folded beneath the same, a centrally perforated back portion engaged with said rim-frame and having an annular recess surrounding the said perfora-

tion at its under side, said rim-frame being permanently clenched upon said back 55 portion and securing said covering in place, a central button portion disposed at the upper side of said rim-frame and back portion of smaller diameter than said rim-frame and back portion, and a shank on 60 said central button portion extending through said cover and through said perforation of said back portion and provided with prongs upset upon said back portion and disposed within said annular recess of 65 said back portion and adapted to secure said button portion to said rim-frame and back portion independently of the securing of said back portion to said rim-frame, and a tuft disposed within said button portion and projecting beyond the upset fronts 70 of said shank and constituting means for securing said button to a garment or the like.

7. In a button, a rim-frame, covering for 75 said rim-frame extending over the same and having its edges folded beneath the same, a centrally perforated back portion engaged with said rim-frame and having an annular recess surrounding said perforation 80 at its under side and an annular raised portion surrounding said opening at its inner side, said rim-frame being permanently clenched upon said back portion and securing said covering in place, said covering 85 extending across the space within said rim-frame above said annular raised portion of said back portion, and a central button portion disposed at the upper side of said rim-frame and back portion of smaller diameter 90 than said rim-frame and back portion, means on said button portion extending through said covering and through said perforation of said back portion and having portions thereof bent into said annular recess 95 to secure said button portion to said rim-frame and back portion independently of the securing of said rim-frame to said back portion, said button portion adapted to be drawn with said covering into engagement with said annular raised portion 100 of said back portion.

In testimony that I claim the foregoing as my invention, I have signed my name hereunder.

MAX MENKIN.
